(57) **CLAIM**

I claim the ornamental design for a set of reconfigurable frames with image block, as shown and described.

(**) Term: **14 Years**

DESCRIPTION

(21) Appl. No.: **29/443,290**

FIG. 1 is a perspective view of a set of reconfigurable frames with image block, showing my new design;

(22) Filed: **Jan. 15, 2013**

FIG. 2 is an enlarged top plan view of one of the frames, the other at least five frames and image block omitted for clarity of design, the bottom plan view being a mirror image thereof;

(51) LOC (10) Cl. 11-02

FIG. 3 is a front elevational view of FIG. 2;

(52) U.S. Cl.

FIG. 4 is a rear elevational view of FIG. 2;

USPC **D11/132**

FIG. 5 is a left-side elevational view of FIG. 2, the right-side

(58) **Field of Classification Search**

elevational view being a mirror image thereof; and,

USPC D11/132, 133, 136, 142, 149, 157, 164;
D6/310, 312; 40/720, 729, 730, 739,
40/741, 743, 762

FIG. 6 is a front elevational view of the image block, all other sides being identical thereto, the frames omitted for clarity of design.

See application file for complete search history.

The broken lines showing additional frames and image blocks

(56) **References Cited**

in FIG. 1 and an image on the front face of the block in FIGS. 1 and 6 depict environmental matter and form no part of the claimed design. The end portions of the frame of FIGS. 2-4 depict the frame having no particular length and form no part of the claimed design.
